Application May 23, 1945, Serial No. 595,328

4 Claims. (Cl. 112—65)

1

This invention relates to an automatic feeding attachment for button hole and snap fastener machines. The principal object of the invention is the provision of an attachment of this character which may be used in conjunction with conventional button hole making machines, and by which a strip of material may be fed through the machine in synchronization with the operation thereof for proper and predetermined spacing of button holes on said strip. Another object of this invention is the provision of an attachment of the character described by which button holes may be sewed into a long strip of material such as a tape at regular or irregular space intervals, or at different intervals on the same strip of material.

The following description of the present invention will be in terms of a button hole making machine and button hole making operations, but it will be understood that this is but illustrative of the general nature of the present invention and that what is said of button holes is equally true of snap fasteners.

A preferred embodiment of this invention is shown in the accompanying drawing in which—

Fig. 1 is a side view of a typical button hole making machine incorporating the attachment herein described and claimed;

Fig. 2 is a front view thereof;

Fig. 3 is a plan view thereof;

Fig. 4 is a section on the line 4—4 of Fig. 3;

Fig. 5 is a somewhat diagrammatic view of a part of a timing mechanism of the device;

Fig. 6 is a diagrammatic view of the electrical system of the attachment; and

Fig. 7 is a fragmentary plan view of a strip of tape showing two series of uniformly spaced button holes formed therein by the machine herein claimed.

The machine herein claimed is provided with a standard button hole making machine 8 mounted on a table 9 and having a conventional belt drive mechanism including a motor M, a freely rotating pulley 10, a drive pulley 10a and an endless belt 11 connecting the motor to the free pulley. A toggle switch 12 connected to the motor by means of cord 13 and to a suitable source of electric current by means of cord 14 controls the motor.

As is the case with standard button hole machines, drive pulley 10a is fixedly mounted on the main drive shaft 15 of the machine. Between successive button hole making operations the drive pulley 10a is prevented from driving the mechanism of the machine by locking finger 16 which

2

locks said drive shaft 15 against rotation by engaging the usual stop cam 17 thereon.

The motor also drives four shafts A, B, C and D respectively, all of said shafts except C being parallel to each other and to the drive shafts of the motor and the machine 8, shaft C lying on a line to which said other shafts are perpendicular. The hook-up between the motor and shafts A, B, C and D is as follows:

10 The motor is connected to a pulley 20 on one end of shaft A by means of endless belt 21. Pulley 22 on the other end of shaft A is connected to a pulley 23 fixed to shaft B by means of endless belt 24. A second pulley 25 on shaft B is connected to pulley 26 on shaft C by means of endless belt 27. A third pulley 28 on shaft B is connected by means of endless belt 29 to pulley 30 on shaft D. Thus it is, that when motor M is started, shafts A, B and D are caused to rotate, but not shaft C. The pulley 26 is not fixed to shaft C but is merely rotatably mounted thereon. A locking mechanism hereinafter described locks the shaft at predetermined intervals against rotation. It will be noted that some of the pulleys are larger or smaller than others. In all cases, however, the driving pulley is smaller than the driven pulley, and hence the arrangement hereinabove described may be considered to be a speed reducing system.

Shafts A and B and the pulleys mounted thereon are idlers and transmitters of power. They serve no other purpose. Shafts C and D however, carry operative parts of the machine.

A wheel or drum 40 is fixedly mounted on shaft C in close juxtaposition to rotatably mounted pulley 26. Pulley 26 has a friction or clutch face on the side of the wheel 40. A compression spring 41 affixed at one end by means of collar 42 to the shaft C and engaging the opposite face of the pulley 26 by means of collar 43 affixed to the other end of said spring, always holds said pulley in frictional engagement with said wheel.

It will be noted that fixedly mounted on shaft C is a notched spacing wheel 45. The notches are spaced at predetermined intervals, the spacing wheel shown in the drawing being provided with two spaced groups of four equally spaced notches each, the spaces between the groups being larger than the spaces between the individual notches thereof.

50 A locking mechanism comprising a pivoted arm 50 pivoted in box 51, has a pin 52 at one end adapted to engage the notches of spacing wheel 45 and a cam member 53 at the opposite end, adapted to be engaged by another cam or trip-
ping member 54. Screws 55 limit the pivotal

movement of arm 50 and leaf spring 56 urges the pin carrying end of said arm to move in the direction of spacing wheel 45, thereby bringing pin 52 into engagement with the notches of said wheel.

It is clear that when pin 52 engages the notches of spacing wheel 45, that wheel and hence the shaft C to which it is affixed and the wheel 40 on said shaft are prevented from rotating despite the presence of rotating pulley 26 which frictionally engages said wheel 40. When the tripping member 54 engages cam 53, it causes arm 50 to pivot against the action of spring 56, thereby disengaging pin 52 from spacing wheel 45. Now that the spacing wheel is released, the shaft C is permitted to rotate and with it wheel 40. Since rotating pulley 26 frictionally engages wheel 40 at all times in response to the action of spring 41 thereon, said wheel, and hence shaft C and spacing wheel 45 will now be caused to rotate. Rotation of the shaft, the wheel 40 and the spacing wheel 45 ceases when tripping member 54 releases the cammed end of arm 50 and the pin carrying end thereof is brought into engagement with the spacing wheel under the influence of spring 56.

Reference to Figure 4 will show that the tripping member 54 comprises a cam member 60 pivotally mounted on an arm 61 which is clamped to a longitudinally movable rod 62. The cam member has a limited range of movement. It cannot pivot above a line drawn through the arm 61, longitudinally thereof. It can pivot downwardly but only against the action of a leaf spring 63. It is clear therefore, that when rod 62 is caused to move downwardly, it carries arm 61 and hence cam member 60 along with it. As the cam member 60 strikes and trips the cam 53 on pivotally mounted arm 50, said arm is caused to pivot and to release spacing wheel 45 as above described. As rod 62 continues its downward movement cam 60 disengages cam 53 and arm 50 pivots back into locking engagement with spacing wheel 45 in response to the action of spring 56. When rod 62 moves upwardly, cam 60 strikes cam 53 and pivots out of engagement therewith. Spring 63 returns cam 60 to its original position.

It will be seen in Figure 1 that rod 62 is pivotally connected to arm 70 which is pivotally mounted at one end on a bracket 71 and which is pivotally connected at the other end to a solenoid 72. The solenoid actuates arm 70 in the usual manner causing longitudinal movement of rod 62 and thereby locking or releasing, as the case may be, spacing wheel 45.

Also pivotally connected to arm 70 is one end of a longitudinally adjustable rod 73 whose other end is pivotally connected to a crank 74 fixed to rotatably mounted shaft 75. Crank 74 is the member which, by means of finger 76, elevates the presser foot 77 in the conventional manner when rod 73 moves downwardly to depress the crank. When rod 73 moves upwardly the crank releases the presser foot which then drops to operative position, also in the conventional manner.

Thus it is that when the solenoid 72 is energized and arm 70 is brought down, two things simultaneously happen: the spacing wheel 45 is released and the presser foot 77 is raised.

Another arm 80 is fixedly mounted on shaft 75 which shaft is connected in conventional manner to the belt shifting and stop cam releasing mechanism of the machine. The arm 80 pivots integrally with said shaft which oscillates on its longitudinal axis when the belt shifting and stop cam releasing mechanism is actuated. The arm

80 engages and closes a normally open electric switch 81 when it pivots downwardly and disengages the same switch when it pivots upwardly.

Switch 81 is but one of three switches in the second of three electric circuits which control the machine. The first circuit has already been described. It includes electric motor M, cord 13, switch 12 and cord 14, the latter being connected to a source of electric current. Referring now to Figure 6, it will be noted that the second circuit in which is found switch 81 comprises a suitable source of electric current, a wire 82 leading therefrom to a toggle switch 83, a wire 84 connecting said toggle switch with normally open switch 81, a wire 85 connecting said normally open switch with a normally closed switch 86, a wire 87 leading from the latter switch to solenoid 72 above mentioned, and a wire 88 leading from said solenoid to the source of current. It is clear from what has thus far been said that when toggle switch 83 is closed by hand and normally open switch 81 is closed by the action of arm 80, the circuit herein designated as the second circuit is made. Between button hole making operations switch 81 is kept closed.

A cam 90 rotatably mounted on the last of the four shafts, shaft D, is adapted to engage and thereby open, the normally closed switch 86. See Figure 5. Cam 90 is rotatably mounted on shaft D. It is engaged by a friction clutch 91 which is fixedly mounted on shaft D, a compression spring 92 on said shaft maintaining said cam at all times in pressure contact with said clutch. In Figure 3 it will be seen that one end of a pivotally mounted locking member 93 is adapted to engage a pin 94 on cam 90 and that the opposite end thereof is adapted for engagement with a plurality of lugs 95 on wheel 40, said lugs being spaced to correspond to the spacing of the teeth on the spacing wheel 45. The locking member in contact with pin 94 locks the cam 90 against rotation. When a lug 95 strikes the locking member the latter is caused to disengage the pin and thereby to release the cam, this being done against the tension exerted by spring 96 on said locking member. When the lug in question disengages the locking member, the latter re-engages the pin 94 in response to the action of spring 96 and the cam 90 is thereby again locked against rotation.

It will be noted in Figure 6 that a normally open switch 100 situated adjacent normally closed switch 86 is adapted to be engaged, and thereby closed, by cam 90. Switch 100 controls the third of the three electric circuits mentioned above. Said third circuit comprises the suitable source of electric current above referred to, wire 82, toggle switch 83, a wire 101 connecting said toggle switch with said switch 100, a wire 102 connecting said switch with a solenoid 103 and a wire 104 leading from said solenoid to the source of current. Thus it is that only when toggle switch 83 is closed and normally open switch 100 is engaged, by cam 90, is solenoid 103 energized.

Careful scrutiny of Figure 5 will disclose that the cam is adapted to engage both switches 86 and 100 at the same time and that rotating as it does in the direction of the arrow, first switch 86 is engaged and thereby opened, and then switch 100 is engaged and thereby closed, switch 86 being still engaged, and then switch 86 is released whereupon it reverts to its normally closed condition, switch 100 being still engaged, and finally switch 100 is released and thereby permitted to revert to its normally open condition.

Solenoid 103 controls a lever 105 which is piv-

oted to a bracket 106. A longitudinally adjustable rod 107 is pivotally connected at one end to lever 105 and at the other end to a rocking arm 110 which is connected to the locking finger 16 above mentioned and belt shifter 111. It is evident that when solenoid 103 pulls rod 107 down, the rocking arm 110 moves the locking finger 16 out of engagement with stop cam 17 thereby permitting rotation thereof and of the drive shaft 15 upon which it is mounted, and simultaneously therewith the belt shifter 111 is caused to shift the belt 11 from the freely rotating pulley 10 to the drive pulley 10a, thereby causing the main drive shaft 15 of the machine to rotate. It will be noted in Figure 1 that rod 107 is provided with a notch 108 which is adapted to receive a pivoted locking arm 112 when the said rod is pulled down a predetermined distance. When the locking arm thus engages the notched rod 107, further vertical movement of said rod is prevented. It becomes immaterial therefore, whether solenoid 103 remains energized or not: the locking arm 112 will be prevented from moving upwardly in response to the action of spring 113 on rocking arm 110. When a complete button hole making operation has taken place the pin 114 on cam 115 strikes the locking arm 112 and causes it to pivot out of engagement with notched rod 107 which is now pulled upwardly by the action of spring 113 on rocking arm 110. Locking finger 16 now re-engages stop cam 17 while at the same time the belt shifter 111 shifts the belt 11 from the drive pulley 10a to the idler 10, all this also in response to the action of spring 113. This has the effect of stopping the button hole making machine 8 from further operation until the next button hole is due to be made.

A complete button hole making operation may now be described.

A long strip of material such as a tape 120 drawn from a freely rotating issuing reel (not shown) is placed in conventional position on the button hole making machine 8. Its free end is drawn under the presser foot 77, through a guide 121, around a roller 122, through a second guide 123, then between wheel 40 and a freely rotating wheel 124 and finally into a collecting basket (not shown) or onto a receiving reel (also not shown). It will be seen in Figure 1 that wheel 124 is carried by a pair of pivotally mounted supports 125 which are pivoted toward the wheel 40 by means of tension springs 126. It will be noted that these supports are pivoted at their lower ends to the frame of the machine. At their upper end is a handle by which they may be pivoted against the action of the tension springs in the direction away from the rest of the machine. This has the effect of bringing the wheel 124 over in the same direction and making tight contact between the tape on the one hand and the wheels 40 and 124 on the other, thereby effecting longitudinal movement of the tape when the wheel 40 is made to rotate as above described. A notched latch 127 holds the wheel 124 a predetermined distance away from wheel 40 to permit drawing the tape therebetween before the button hole making operations begin or to permit withdrawing the tape when these operations are concluded.

This is accomplished when the notch of latch 127 is caused to engage the axle of wheel 124. This can only be done by moving supports 125 outwardly in the direction away from wheel 40. Therefore, when the latch 127 is in engagement, by means of its notch, with the axle of wheel 124, a considerable space is provided between

the two wheels 40 and 124 through which the tape may be drawn.

Switch 12 is now closed starting motor M and causing rotation of shafts A, B and C. The three switches 81, 83 and 86 are now closed and the second circuit above described which these switches control is likewise closed. Solenoid 12 which is in said circuit becomes energized.

Solenoid 12 acts to free spacing wheel 45 by pivoting arm 50 and hence pin 52 out of engagement with one of the notches in said wheel and at the same time to raise the presser foot 77 by pulling rod 73 down. heel 40 is now free to rotate under the influence of rotating friction pulley 26 and in so doing it draws the tape a distance determined by the space separating adjacent notches in the spacing wheel. It will be recalled that arm 50 is not held out of engagement with the spacing wheel, but instead tripped out of engagement therewith. Arm 50 re-engages and locks the spacing wheel at its first opportunity, said opportunity being presented when the notch immediately following the first mentioned notch is brought into engageable position with respect to pin 52.

Before, however, said second notch moves into engageable position, and in consequence of the limited angular movement of wheel 40, locking member 93 is tripped to release cam 90. Said cam now itself engages in angular movement under the influence of rotating friction clutch 91, the extent of such movement being controlled by the space separating adjacent lugs 95 on wheel 40. As has already been indicated, lugs 95 are spaced to correspond to the spacing of the notches in the spacing wheel, but the notches occupy advanced positions: that is the notches are timed for disengagement before the corresponding lugs disengage the locking member 93 and they are timed for re-engagement before the lugs reengage said locking member.

After the second notch is engaged by pin 52, the cam 90 contacts and opens switch 86, thereby breaking the second circuit above described, and de-energizing solenoid 12. The presser foot now drops in response to the usual spring action exerted thereon and another conventional spring (not shown) raises the arm 74 and thereby elevates the tripping member 54 and the rod of solenoid 72 readying these members for repetition of the action above described.

The tape having been moved a predetermined distance and the presser foot being down, the machine 8 is now ready to perform the usual button hole making operation on said tape. Cam 90 is still moving and it now contacts and closes switch 100 thereby closing the third circuit above described. Solenoid 103 is energized pulling rod 107 down until the notch 108 therein is engaged by latch 112, thereby causing the belt shifter 111 to move the belt 11 from the idling pulley 10 to the drive pulley 10a and at the same time causing the pin 16 to release the stop cam 17. The machine and the trimmer mechanism now operate in conventional manner.

Switch 86 is still held open by cam 90. When switch 81 is released by arm 80 which is connected to the belt shifting and stop cam releasing mechanism, said switch 81 opens and it therefore becomes immaterial that cam 90 releases switch 86 and permits it to close. It will be recalled that latch 112 is now in locking engagement with rod 107. Such being the case it is immaterial that cam 90 releases switch 100 and permits said switch to open.

The operation of the machine continues until a complete button hole is made. When this is done pin 114 on cam 115 causes latch 112 to disengage rod 107. The latter now moves up in response to the action of spring 113 and also in response to said action the belt shifter returns the belt 11 to the idler 10 and the locking finger 16 re-engages the stop cam 17. At this moment the trimming mechanism trims the top and bottom thread in the usual way. A complete button hole making operation has now been described and the procedure is repeated for the next button hole.

The machine above described is but a preferred embodiment of the present invention and many modifications may be incorporated therein without departing from the basic principles of the invention. For example, hydraulic or compressed air means might be used to take the place of the solenoids herein described and it is believed that they would serve the same purpose as the solenoids equally well.

We claim:

1. An automatic feeding attachment for button hole making machines comprising a work feeding means and a timing mechanism which actuates the work feeding means between buttonhole making operations, said work feeding means including a wheel frictionally engaged for rotation and frictionally engaging the work for longitudinal movement thereof, said timing mechanism consisting of a notched spacing wheel fixed to a common shaft with said work feeding wheel, and a locking member which engages the notches on said spacing wheel and locks said wheel and the work feeding wheel against rotation during button hole making operations of said machine, and unlocks said wheels in the intervals between button hole making operations of said machine, thereby permitting the work feeding wheel to move the work longitudinally.

2. An automatic feeding attachment for button hole making machines comprising a work feeding means including a feeding wheel which is adapted for intermittent angular movement and which frictionally engages the work for longitudinal movement thereof, a timing mechanism which causes angular movement of said feeding wheel at spaced, predetermined intervals, and a second timing mechanism which actuates the button hole making machine in the intervals between movements of said feeding wheel, said second timing mechanism consisting of a cam wheel which actuates the electric switches controlling the button hole making machine, said cam wheel being frictionally engaged for rotation, and a locking member engaged by said feeding wheel which locks said cam against rotation when the feeding wheel moves, thereby stopping the button hole making machine when it is time to advance the work.

3. An automatic feeding attachment for button hole making machines having the usual presser foot for holding the work during the button hole making operation, said attachment, comprising a work feeding means including a feeding wheel which is adapted for intermittent angular movement and which frictionally engages the work for

longitudinal movement thereof, a timing mechanism which causes angular movement of said feeding wheel at spaced, predetermined intervals, said timing mechanism comprising a rotating wheel which frictionally engages the feeding wheel to cause rotation thereof, a notched wheel connected to said feeding wheel, and a solenoid controlled mechanism which intermittently engages the notched wheel to lock it and the feeding wheel against angular movement thereof, and intermittently disengages the notched wheel to free it and the feeding wheel for angular movement thereof in response to the action of the rotating wheel on the feeding wheel, said solenoid controlled mechanism being also connected to the presser foot of said button hole making machine for intermittently disengaging said presser foot from the work to free the work for longitudinal movement thereof in response to the action of the feeding wheel thereon, and a second timing mechanism which actuates the button hole making machine in the intervals between movements of said feeding wheel, said second timing mechanism consisting of a cam wheel which actuates the electric switches controlling the button hole making machine, said cam wheel being frictionally engaged for rotation, and a locking member engaged by said feeding wheel which locks said cam against rotation when the feeding wheel moves, thereby stopping the button hole making machine when it is time to advance the work.

4. An automatic feeding attachment for button hole making machines comprising a work feeding means including a feeding wheel which is adapted for intermittent angular movement and which frictionally engages the work for longitudinal movement thereof, a timing mechanism which causes angular movement of said feeding wheel at spaced, predetermined intervals, and a second timing mechanism which actuates the button hole making machine in the intervals between movements of said feeding wheel, said second timing mechanism consisting of a cam wheel, a rotating wheel which frictionally engages the cam wheel to cause rotation thereof, a locking member which is actuated by the feeding wheel when the timing wheel moves, and which intermittently locks said cam wheel against angular movement thereof, and intermittently frees said cam wheel for angular movement thereof in response to the action of the rotating wheel thereon, and a solenoid controlled mechanism actuated by the cam wheel which controls the operation of the button hole making machine.
